CAPSULATED BULB AND METHOD OF
MAKING THE SAME

Philip C. Demarest, Pine Brook, Harry R. Foster, Montville, and Elmo E. Crump, West Caldwell, N.J., assignors to Ohmega Laboratories, Pine Brook, N.J., a corporation of New Jersey

Filed July 31, 1961, Ser. No. 128,245

1 Claim. (Cl. 313—317)

This invention relates to capsulated bulbs or tubes which at some time during the production must be substantially gas-free. More particularly the invention relates to capsulated bulbs in which the presence of gas during the production thereof would be undesirable.

In order to exemplify the present invention it will hereinafter be described with relationship to a bulb of reduced size. It is, however, to be understood that this description is merely exemplary of the facets in which the present invention can be efficiently applied and that the description referring to miniaturization and microminiaturization is in no way to be construed as limiting the scope of the invention or the appended claims.

A serious problem heretofore has existed in the production of bulbs which are extremely miniature in size. This has existed because of the presence of undesirable gas in the bulb at some time during its production. Such gas formations impair the efficiency and functioning of the bulb and prior to the present invention prevented the utilization of miniature and microminiature bulbs as a component in electronic devices for use in airplanes, rockets, missiles, the medical profession and various other areas of industry. The gas formation, as for example that caused by water vapor and hydrogen emitted in the fusing of the gas bulb and effected in the seal of the bulb has heretofore seriously disturbed the functioning of bulbs of miniature size. The present invention, therefore, relates to and solves the problem of exhaustion of the undesirable gases which are formed during the production of the bulb itself. The invention contemplates the removal of all undesirable gases so that the bulb chamber may be gas-free if desired. However, by the use of the simple expeditious means utilized in the removal of the gases of undesirable nature it is also possible after such removal to insert into the bulb any gases whose artificial introduction may add to the proper functioning of the bulb itself.

In its broader aspects the present invention contemplates the provision of means in the wall of the bulb itself through which the undesirable gas may be exhausted and while the gas is exhausted or after the introduction of desirable gas, the means themselves may be sealed off with the remainder of the bulb to provide a highly efficient gas-free or properly gas filled bulb.

More specifically, the present invention provides a miniature metallic tube of high resistance to heat and electricity adapted to be passed through a wall of the bulb and serve as a gas exhaust vent, and thereafter, if desired, as a gas intake tube. The tube is unaffected by the application of heat to fuse and seal the bulb and is itself thereafter closed and sealed as by the application of heat at a high temperature to fuse the walls of the tube.

In carrying out the invention, the bulb is formed with an aperture for the assembly of the filament (and any other parts) in the bulb casing. A small-bore tube is formed of copper wire clad or plated with platinum, which wire is then cut into short lengths and the cuttings subjected to a copper-etching acid bath until the copper is completely etched from within the platinum. The short platinum tube is then inserted in an aperture in the wall of the bulb casing and secured therein. Heat is then applied to fuse the area of the bulb around the filament assembly aperture to hermetically secure it in the bulb. The

position of the tube is such that one end opens into the bulb chamber and the other end opens exteriorly of the bulb, and under the influence of the vacuum the gas exhaustion continues to remove the gas generated by the fusing of the glass. If desired proper gases may be introduced through the same tube. Thereafter the gas-free or appropriately gas filled bulb is finally prepared by hermetically sealing a portion of the tube by heat fusing the walls of the tube. Thus the intake of air or undesirable gases or the escape of desirable gases through the tube is prevented. The bulb chamber is thus completely sealed.

In the accompanying drawings, the invention has been shown merely by way of example and in preferred form and obviously many variations and modifications may be made therein which will still be comprised within its spirit. It is to be understood, therefore, that the invention is not limited to any specific form or embodiment, except insofar as such limitations are set forth in the appended claims.

Referring to the drawings:

FIG. 1 shows a section of the wire employed for producing a metallic tube to be used in connection with the present invention;

FIG. 2 shows a tube formed from the wire shown in FIG. 1;

FIG. 3 is a transverse section of a plastic mandrel wound with wire of the character shown in FIG. 1;

FIG. 4 is a side elevation of the mandrel and wire winding shown in FIG. 3 when encased in plastic material, and showing the slicing thereof into short sections of predetermined length;

FIG. 5 is a view showing a metal tube freely assembled with a short length of glass tubing;

FIG. 6 shows the metal tube surrounded by a ball into which the glass tube of FIG. 5 has been coalesced;

FIG. 7 shows the capsulated bulb with the glass balls assembled at both ends with one of said glass balls carrying the tubing provided by the present invention;

FIG. 8 shows the structure of FIG. 7 after the glass balls have been melted to form the final bulb with the tubing sealed off;

FIG. 9 shows the bulb in its preparatory state like FIG. 7 with one of the leads passing through the glass balls at one side also constituting the tubing;

FIG. 10 shows a modified form of the present invention in which an electric resistance wire filament is attached to leads formed with a coalesced glass ball thereon assembled in the open end of the glass tubing;

FIG. 11 shows still another modified form of the present invention in which the leads are attached to cathodes with the leads formed with a coalesced glass ball thereon assembled in the open end of the glass tubing with a provision of, for example neon lights; and

FIG. 12 shows another modified form of the glass ball with the glass tubing coalesced into a ball around the leads into the filaments and assembled in the open end of the capsule.

In accordance with the preferred form of the present invention the bulbs or capsules of the microminiature electric device shown as exemplary herein is formed in a series of steps. Initially leads are secured passing through coalesced glass balls. A filament joins the interior portions of the leads and the balls are inserted with one ball at each end of minute glass tubing. A source of electric current is passed through one of the leads producing enough heat to melt the glass ball and the contiguous part of the glass tube so that the glass flows together to make a hermetic junction and form a capsule. Thereafter the ends of the leads extend exteriorly of the capsule to serve as electrical terminals for the component within the capsule.

While the wire has been described as comprising two leads joined together with an intermediate filament, the essential requirement is that both ends of the leads be available for connection to a source of electric current in order that the wire may be heated sufficiently to melt the glass ball. The exact shape of the filament and leads is secondary to this basic requirement and it may adopt various forms as hereinafter described. The ball itself is formed in a series of steps according to the present invention, as for example by providing a short length of minute hollow glass tubing through which the lead is passed and thereafter applying a suitable voltage to the ends of the leads to drive an electric current therethrough. This will heat the wire sufficiently to melt the short pieces of glass tubing and cause it to coalesce into a ball which attaches itself to the leads and secures the lead within the ball.

According to the present invention, successive manufacturing steps are involved, and after certain steps have been performed the product produced up to that point may be at a stage where it is suitable for commercial marketing even though additional steps have to be performed in the production of the ultimate finished article. It is to be understood, therefore, that the invention is not limited to the ultimate product or to the entire succession of steps involved in producing the capsulated electric lamp.

The present invention utilizes a small metal tube formed with a minuscule bore. According to a preferred procedure, and referring to FIGS. 1 to 4, a tube 10 approximately $\frac{1}{2}$ " in length is produced with a minuscule bore approximately .0003" in diameter, although such dimensions may vary within a range of $\frac{3}{16}$ " to $\frac{1}{16}$ " and of .005" to .0003", or less, respectively. The tube 10 is preferably made of platinum, and obviously it is too delicate to be made by machining, such as by drilling or drawing. The preferred method of forming the tube 10 is to clad a fine copper wire 11 with platinum 12 and drawing it down to the desired size. The platinum-clad wire 13 is then subjected to a bath in a copper-etching acid which will etch out or erode away the copper and thus produce the platinum tube.

Another problem is presented in cutting the platinum-clad wire into predetermined short lengths, because it is essential that the cutting operation shall not compress the wire 13, whereby it might swage the platinum over the cut end thereof and thereby prevent the etching out of the copper to form the tube. Accordingly, it is proposed by the present invention to wind the platinum-clad copper wire 13 on a mandrel 14 formed of epoxy resin plastic or other suitable material which will be destroyed in the copper-etching acid bath.

Thus referring to FIGS. 1-4 a length of the platinum-clad wire 13 is wound upon the mandrel 14 to build up a winding 15 of the wire thereon. When a sufficient winding 15 has been formed the mandrel 14 with its winding 15 is immersed in a bath of epoxy resin or other suitable material, heated to a fluid condition, to encase the winding and at the same time flow between and encase the individual wires 13 of the winding. Upon removal from the plastic bath, the plastic chills to form a block 16 of plastic-encased wire (see FIGS. 3 and 4). The block 16 may then be severed into slices 17 of predetermined thickness to form the desired lengths of platinum-clad copper wire 13 without danger of collapsing the wire during the slicing operation. Thereafter the slices 17 may be sanded and polished to remove any resulting platinum coating over the ends of the exposed copper cores. The slices 17 are then placed in a heated bath of copper-etching acid. In an acid bath comprising approximately 50% nitric acid and 50% water, which is heated to a temperature of approximately 100° to 110° C., the plastic in the slices 17 will dissolve in approximately 1 hour, and approximately 8 to 9 hours more is required to completely etch out the copper wire 11 from within

10

the platinum coating 12. The plastic is substantially destroyed by the acid bath and the etched copper gives off hydrogen and salts, the hydrogen evolving as a gas and the salts going into solution in the bath. Thereafter the tubes 10 (FIG. 2) each formed by a platinum wall 20 surrounding a minuscule bore 21, are removed from the acid bath and baked under vacuum in an oven heated to a temperature in the range 1500°-2000° F. for a period of approximately 4 to 5 hours to remove all gas in or on the surface of the metal.

Preparation of the tube 10 for use in the formation of a bulb 25 for a capsulated electric lamp 35 (FIG. 8) is shown in FIGS. 5 and 6. A preferred procedure is to cut from a length of glass tubing a portion 27 which is shorter than the length of the tube 10, insert the tube 10 into the portion 27 to bear against the inner surface and extend beyond the opposite ends thereof (FIG. 5), and then by the application of heat to the portion 27 melt and cause the glass thereof to coalesce into a ball 28 tightly sealed around the tube 10 intermediate its opposite ends. This construction may be utilized in the various forms of bulbs hereinafter described for illustrative purposes.

In the embodiment of the present invention shown in FIGS. 7 and 8, the glass ball 28 is formed in the manner set forth, with an anchor or lead 29 secured and coalesced in the ball above the tube 10. A similar glass ball 30 having a lead or anchor 31 but without the tubing 10 is also provided. A filament 32 extends between the exposed portions of the leads or anchors 29 and 31 as shown. The unit is then placed within the glass tubing 33 so that the glass balls are disposed at each end thereof being preferably located so that the major portion of each ball lies within the tubing 33 at its respective ends. The application of heat to the end of the tubing 33 and the balls 28 and 30 melts and causes them to fuse together at each end to form a permanent tight seal as shown in FIG. 8 with the filament 32 permanently secured therein. A capsulated bulb 35 is thereby provided.

In the fusing of the glass tubing 33 to secure the filament 32 therein, gas, which is primarily water and hydrogen, is emitted into the chamber 36 of the bulb 35, and according to the best practice known heretofore such gas would have become trapped in the chamber 36. According to the present invention, however, the gas is withdrawn through the tube 10 by the vacuum maintained around the bulb 35, whereby the chamber 36 is made substantially gas free. While the bulb 35 remains under the condition of vacuum, heat of sufficient intensity is applied to a portion of the tube 10 exposed exteriorly of the bulb 35 (FIG. 8) to melt and fuse the walls thereof and hermetically seal the bulb 35. As already stated, the withdrawal of substantially all gas, including that evolved in securing the filament 32 in place, enables the production of a capsulated electric lamp smaller than any which it has been possible to make heretofore. Moreover, such lamps can be economically produced by the use of multiple unit lamp jigs wherein a plurality of the bulbs 35 are assembled and closed, evacuated and sealed all at the same time.

Another application of the present invention is shown in FIG. 9. In this instance the bulb is formed substantially as heretofore described with the glass balls 28 and 30 being located within the glass tubing 33 and carrying leads 29 and 31 coalesced therein with the exposed inner portions being secured to a filament 32. In this application of the present invention, however, the lead 31 also comprises a tubing whose bore 10a extends through the glass bulb 30 and into the chamber 36 as shown. The lead, therefore, also functions as the tube itself through which the undesirable gases may be withdrawn prior to sealing off the end of the tubing.

FIG. 10 discloses another variant of the present invention. As shown, two leads 40 and 41 are coalesced within a glass ball 42 with the inner exposed ends thereof

passing through the glass ball. A wire filament 43 doubled back to form a open bight is secured to each of the ends of the filaments 40 and 41. By the application of heat, the glass ball and the glass tubing 44 are melted and fused at one end of the tubing 44. The platinum tube 10 is utilized, at the end of the tubing 44 this section having been prepared as illustrated in FIG. 6 with the ball being fused and melted to the glass tubing 44. The application of heat to fuse the glass ball 42 and the tubing 44 will accomplish the final bulb.

FIG. 11 shows another modified form of electric lamp wherein the leads 50 and 51 coalesced within the glass ball 52 carry cathodes 53 and 54. In this construction, after the undesirable gases are withdrawn from the chamber 55 through the tubing 10, a desirable gas, such as neon, may be introduced into the chamber through the tubing 10 before the tubing is sealed off to form a completely sealed capsulated neon lamp. It may be seen that the present invention contemplates the withdrawal of undesirable gases at any time during the production of the lamp and that if desirable gases are necessary they may be introduced through the same means used to withdraw the undesirable gases. Thus, many types and kinds of bulbs may be formed under this present invention.

Another application of the present invention is shown in FIG. 12 wherein a lamp element 60 is formed closed at one end and open at the other end. In this instance the tube 10 and filament 61 are both assembled in the open end of the glass tubing encased in a glass ball 62 with leads 63 and 64 passing through the ball attached to the filament. When heat is applied to the ball and the surrounding portion of the glass tubing, a tight seal is formed which also insulates the leads and the tubing one from the other. After the gas is withdrawn, the exposed end of the tube 10 is fused to seal the bulb 60.

In the foregoing specification and in the appended claims, the word "bulb" as used includes any incandescent lamp, electronic tube, or other such article which requires that the interior thereof at some time during its construction be in a condition of substantial vacuum, i.e., exhausted or substantially exhausted of air or gas. It is also intended that the word "gas" shall include various different types of gases.

As already stated, preferred embodiments of the invention have been shown and described herein and many

modifications and variations thereof may be made. Furthermore, different modes of application of the invention may occur to those skilled in the art without departing from its spirit. Therefore, it is to be understood that the appended claim is not to be construed as being limited beyond the scope of the language expressly set forth therein.

We claim:

A capsulated bulb comprising: a substantially cylindrical glass wall pervious to light; a fine metal filament within said bulb; two separately-formed glass end members fused to said substantially cylindrical glass wall, one at each end, and each of said members having an axial thickness substantially greater than the thickness of said wall; two relatively heavy metal wires substantially parallel to the axis of said cylindrical wall, one of said wires extending through each of said end members and having an end of each of said relatively heavy wires electrically and mechanically attached to one end, respectively, of said filament to support said filament within the space of said bulb; a tube of fusible metal formed with a minuscule bore and hermetically sealed into one of said end members and extending substantially parallel to the axis of said bulb and spaced from said relatively heavy wire, with one end of said tube opening interiorly of said bulb to evacuate gas from said bulb, said bulb having a substantially gas-free interior.
